VALVE STRUCTURE

Albert B. Campbell, Bensenville, Ill., assignor to Campbell Products Co., a corporation of Illinois

Application August 28, 1953, Serial No. 377,048

7 Claims. (Cl. 251—144)

This invention relates to a valve structure, and more particularly to a valve for a lather producing machine, such machines commonly being used in barbershops.

The improved valve constituting the present invention is for use with the lather producing machines disclosed in my prior Patents 2,191,450, granted February 27, 1940, 2,323,377, granted July 6, 1943, and 2,495,441, granted January 24, 1950, all for Lather Producing Machines.

One of the primary difficulties in the operating of currently used lather producing machines is the tendency of the valve regulating the flow of liquid soap into the lathering chamber to become clogged with dried soap. An accumulation of dried soap in and about the moving parts of the valve prevents the valve from operating at all. Because of the almost constant use of these machines in places like barbershops, accumulations of dried soap in the valve mechanism build up rapidly, necessitating frequent cleaning of the valve with consequent loss of time and use of the machine.

By means of the present invention it is possible to provide a self-cleaning valve so as to eliminate the need for frequent cleaning. The present invention provides a valve mechanism with sufficient unused space in and about the working parts so that infiltration of liquid soap beyond the self-cleaning structure will not cause immediate inoperativeness of the valve.

The valve constituting this invention is removably mounted in a lather producing machine which has a liquid soap receptacle, a lather producing chamber and a passage between them. The most convenient place for mounting the valve is in the liquid soap receptacle, with the passageway being formed to provide a valve seat. The closure portion of the valve will yieldingly bear against the seat, consequently the valve stem associated with the closure portion will be in contact with liquid soap. Essentially, the valve constituting my invention includes a valve seat, a valve closure element, a stem element, a spring associated with the stem element for urging the closure element against the seat, a lever for opposing the spring so that the valve closure element may be unseated, and a stem guide member. The valve stem element is slidably received into the stem guide member, the stem guide member being removably mounted in the liquid soap receptacle. The sliding motion of the valve stem element into the stem guide member produces a wiping action which keeps the portion of the valve stem element inside the stem guide member substantially free of soap.

The invention will be described as related to the accompanying drawings in which:

Fig. 1 is a side elevational view of applicant's invention assembled in a lather producing machine;

Fig. 2 is a sectional view centrally through the valve structure showing one particular form of the invention;

Fig. 3 is a sectional view taken along the line 3—3 of Fig. 2; and,

2

Fig. 4 is a sectional view taken along the line 4—4 of Fig. 2.

An embodiment of the invention is assembled in a lather producing machine, generally designated 10. The lather producing machine 10 comprises a housing 11, a liquid soap receptacle 12, a lather producing chamber 13 with outlet 14, a passageway 15 between the liquid soap receptacle 12 and the lather producing chamber 13, a valve structure generally designated 16, and a motor 17 for operating a lather producing screw (not shown) in lather producing chamber 13.

The details of construction of the valve may best be seen in the enlarged views, Figs. 2, 3 and 4.

Referring to Fig. 2, the valve 16 is removably mounted in liquid soap receptacle 12. Sleeve-like stem guide member 18 is inserted in circular opening 19 in the housing 11, being supported on housing 11 by top flanges 20 and 21. In the preferred form, stem guide member 18 is a plastic tube having a wide portion 22 and a constricted portion 23, the wide and narrow portions being connected by transverse annular shoulder 24. A plurality of longitudinal ribs 25, integral and substantially coextensive with the wider portion 22, are provided in stem guide member 18.

Tubular valve stem element 26, having a wide portion 27 and a constricted portion 28 connected by transverse shoulder 29, is slidably received into stem guide member 18. Thus, the stem guide member 18 acts like a sleeve or casing for the stem element 26, with the constricted portion 28 of the valve stem element being slidably received in the constricted portion 23 of the stem guide element 26 and the wider portion 27 of the stem element being slidably received in the ribbed or wider portion 22 of the stem guide member 18. In the preferred embodiment, stem guide member 18 and valve stem element 26 are cylindrical, the outside diameter of the wider portion 27 of valve stem element 26 and the internal diameter of the wider portion 22 of stem guide member 26 differing by the thickness of the longitudinal ribs 25. This difference in diameters provides annular spaces 30 between the outer surface of the wide portion 27 of valve stem element 26 and the inner surface of ribbed portion 22 of stem guide member 18.

Rod-like valve closure element 31 is secured to constricted portion 28 of valve stem element 26 so as to provide a substantially coaxial extension thereof. One form of securing is shown in Figure 2 wherein valve closure element 31 is press-fitted in a cylindrical hole in the constricted portion 28 of valve stem element 26. The closure element 31 can thus be of a different material than the valve stem element 26. In the preferred embodiment both the stem guide member 18 and the valve stem element 26 are plastics, being alathon and nylon respectively, while the closure element 31 is a metal. An obvious advantage of a metal closure element is that it will be more resistant to wear caused by frequent seating. These materials have been found to form a very satisfactory valve. However, any other suitable materials can be used.

The bottom 32 of the liquid soap receptacle 12 is provided with a circular-shaped opening or passageway 15 leading to lathering chamber 13. The upper rim 33 of passageway 15 forms a valve seat.

Valve closure element 31 is provided with a needle valve adapted to seat against rim 33 so as to seal passageway 15 against flow of liquid soap. The constricted portion 28 of the valve stem element 26 is of such a length with relation to the constricted portion 23 of stem guide member 18 that upon seating of the valve closure element 31 on valve seat or rim 33 of passageway 15, portions of the constricted portion 28 of the valve stem element 26 extend above and below the constricted por-

tion 23 of stem guide member 18. The extension of the constricted portion 28 of the valve stem element 26 above the constricted portion 23 of stem guide member 18 provides an annular space 34, the height of which is determined by the transverse shoulders 24 and 29 of the stem guide member 18 and the valve stem element 26, respectively.

Cover member 35 is removably secured to housing 11 by bolts 36 extending through openings 37 therein and are threadably received into threaded openings 38 in housing 11. Cover member 35 is provided with inset portion 39 adapted to receive flange 20 of stem guide element 18. Stem guide element 18 is held removably locked in position by the cooperation of cover member 35, housing 11, and side wall 40 of liquid soap receptacle 12.

Located on and integral with the surface of cover member 35 internal to valve 16, and in the axis of cylindrical valve stem element 26, is conical spring centering protrusion 41. Extending between cover member 35 and transverse shoulder 29 of valve stem element 26 is coiled spring 42. The end of coiled spring 42 bearing against cover member 35 is concentric to conical spring centering protrusion 41.

Integral with valve stem element 26 is top annular flange 43. Top flange 21 of stem guide member 18 is provided with an upstanding rib 44. Rockingly mounted on rib 44 is lever member 45. Operating arm 46 of lever member 45 bears against the lower surface of top flange 43 of valve stem element 26. The power lever arm 47 of lever member 45 bears against finger piece or plunger 48. Plunger 48 is slidably mounted in top opening 49 of cover member 35.

In the preferred embodiment, lever member 45 has a pair of power arms 47 bearing against oppositely situated portions of the bottom periphery of hollow cylindrical plunger 48. Web portion 50 extending between power arms 47 is restricted so as not to extend across the hollowed out portion 51 of plunger 48. Thus, an extension member (not shown) may be inserted into the hollowed out portion 51 of plunger 48 to operate a switch (not shown) on motor 17.

In operation, whenever lather is desired, plunger 48 is manually depressed. By means of the aforementioned extension (not shown), a switch (also not shown) on motor 17 will be turned on, causing the lathering screw mechanism (not shown) in lathering chamber 13 to operate. At the same time, the depression of plunger 48 exerts pressure against power lever arms 47 of lever member 45, causing the lever member to rotate about upstanding rib 44 which acts as a fulcrum. By this action the operating arm 46 of lever member 45 is rotated upwardly, applying pressure against the lower surface of top flange 43 of valve stem element 26. The pressure against flange 43 causes the entire valve stem to rise, overcoming the pressure exerted by coiled spring 42 and compressing the spring, thereby raising valve closure element 31. As valve closure element 31 is raised, passageway 15 is opened and liquid soap can flow from the liquid soap receptacle 12 into the lathering chamber 13 from which it is expelled through lather outlet 14.

Upon opening the valve, the sliding fit between the external surface of constricted portion 28 of valve stem element 26 and the internal surface of constricted portion 23 of stem guide member 18 permits the inner surface and especially the external lip of the constricted portion 23 of stem guide member 18 to shear or wipe off any liquid soap particles that might adhere to constricted portion 28. Should any soap particles manage to pass this sliding tolerance they would accumulate in space 34 above shoulder 24 and still not prevent operation of the valve. Further accumulation of soap above shoulder 24 would fill annular spaces 30 between the wider portions of valve stem element 26 and stem guide member 18, which still would not impair operation of

the valve. However, should extensive accumulation of soap occur as indicated above, the valve can be cleaned readily by removing bolts 36 and lifting out the entire valve.

Upon release of manual pressure from plunger 48, lever member 45 no longer exerts pressure against top flange 43 of valve stem member 26, so that compressed spring 42 can expand and force valve stem element 26 downwardly, seating valve closure element 31 against valve seat 33, thereby sealing passageway 15 against further flow of liquid soap.

While I have shown and described a certain embodiment of my invention, it is to be understood that it is capable of many modifications, changes, therefore, in the construction and arrangement may be made without departing from the spirit and scope of the invention as disclosed in the appended claims.

I claim:

1. In a lather producing machine having a liquid soap receptacle and a passageway capable of serving as fluid outlet means, a valve seat positioned in said receptacle communicating with said passageway, and a valve assembly positioned in said receptacle in opposed, spaced relationship to said valve seat, said assembly comprising an elongated tubular valve stem guide, an elongated valve stem slidably mounted in said guide, a valve closure element secured to one end of said valve stem capable of extending beyond the confines of said guide and being sealably seated in said valve seat, an elongated tubular cavity formed at the other end of said valve stem, resilient means positioned in said cavity serving to urge said valve closure into sealing relationship with said valve seat, pivotal means operatively associated with said guide for selectively sliding said valve stem and valve closure element away from said valve seat thus enabling said valve stem to compress said resilient means and unseat said valve closure element.

2. In a lather producing machine having a liquid soap receptacle and a passageway capable of serving as fluid outlet means, a valve seat positioned in said receptacle communicating with said passageway, and a valve assembly positioned in said receptacle in opposed, spaced relationship to said valve seat, said assembly comprising an elongated tubular valve stem guide, an elongated valve stem slidably mounted in said guide, a valve closure element secured to one end of said valve stem capable of extending beyond the confines of said guide and being sealably seated in said valve seat, an elongated tubular cavity formed at the other end of said valve stem, resilient means positioned in said cavity serving to urge said valve closure into sealing relationship with said valve seat, said resilient means being retained in said cavity by stop means, pivotal means operatively associated with said guide for selectively sliding said valve stem and valve closure element away from said valve seat thus enabling said valve stem to compress said resilient means and unseat said valve closure element.

3. A fluid control device comprising: a receptacle having a passageway capable of serving as fluid outlet means, a valve seat positioned in said receptacle communicating with said passageway, and a valve assembly positioned in said receptacle in opposed, spaced relationship to said valve seat, said assembly comprising an elongated tubular valve stem guide having a plurality of internal longitudinal ribs extending therein, an elongated valve stem slidably mounted in said guide so that said ribs frictionally contact said valve stem, a valve closure element secured to one end of said valve stem capable of extending beyond the confines of said guide and being sealably seated in said valve seat, an elongated tubular cavity formed at the other end of said valve stem, resilient means positioned in said cavity serving to urge said valve closure into sealing relationship with said valve seat, pivotal means operatively associated with said guide for selectively sliding said valve stem and valve closure element away from said valve seat thus enabling said valve stem to

compress said resilient means and unseat said valve closure element.

4. A fluid control device comprising: a receptacle having a passageway capable of serving as fluid outlet means, a valve seat positioned in said receptacle communicating with said passageway, and a valve assembly positioned in said receptacle in opposed, spaced relationship to said valve seat, said assembly comprising an elongated tubular valve stem guide having a constricted portion at one end, an elongated valve stem slidably mounted in said guide, a valve closure element secured to one end of said valve stem capable of extending beyond the confines of said guide and being sealably seated in said valve seat, said valve stem being shaped so as to frictionally engage the constricted portion of the guide at all times, an elongated tubular cavity formed at the other end of said valve stem, resilient means positioned in said cavity serving to urge said valve closure into sealing relationship with said valve seat, pivotal means operatively associated with said guide for selectively sliding said valve stem and valve closure element away from said valve seat thus enabling said valve stem to compress said resilient means and unseat said valve closure element.

5. In a lather producing machine having a liquid soap receptacle and a discharge passageway, said passageway forming a valve seat, a valve in said passageway comprising a valve closure element, means for seating and unseating the valve closure element, a valve stem between the valve closure element and said seating and unseating means, said valve stem comprising a cylindrical element having wide and constricted portions, a stem guide member removably mounted in said soap receptacle, said stem guide member comprising a tube having wide and constricted portions, said stem member being slidably received in said guide member, a plurality of internal longitudinal ribs integral with the wide portions of said guide, the external diameters of the wide and constricted portions of the valve stem being substantially the same as the internal diameters of the ribbed and constricted portions, respectively, of the stem guide member, and wherein the constricted portions of the stem guide mem-

ber and valve stem are adjacent the valve closure member.

6. A valve of the character described in claim 5 wherein the constricted portion of the valve stem is of such a length with relation to the length of the constricted portion of the stem guide member that upon seating of the valve closure member, portions of the constricted portion of the valve stem extend above and below the constricted portion of the stem guide member whereby accumulation of liquid soap within and above the constricted portion of the stem guide member will not prevent the valve from being seated.

7. In a lather producing machine having a liquid soap receptacle and a discharge passageway, said passageway forming a valve seat, a removable valve in said passageway comprising a valve closure member, valve stem adjacent said valve closure member, the end of said valve stem remote from the said valve closure having a peripheral flange, a cover member removably secured to said lather producing machine, a stem guide member adjacent said cover member, wherein the valve stem is slidably received in the said stem guide member and the said cover member, a spring member between said valve stem and said cover member for urging said valve stem and valve closure member against the valve seat, and a lever member pivotably mounted on said stem guide member and within said cover member wherein one lever arm is adapted to bear against the peripheral flange of said valve stem to oppose the urging action of said spring and the other lever arm is adapted to receive externally applied pressure.
